Inventor:
William O. Gottwals,
by Graham Low,
Atty.

UNITED STATES PATENT OFFICE.

WILLIAM O. GOTTWALS, OF WASHINGTON, DISTRICT OF COLUMBIA.

BILL-FILE.

SPECIFICATION forming part of Letters Patent No. 527,278, dated October 9, 1894.

Application filed May 2, 1894. Serial No. 509,816. (No model.)

To all whom it may concern:

Be it known that I, WILLIAM O. GOTTWALS, a subject of the Queen of Great Britain, who have declared my intention to become a citizen of the United States of America, residing at Washington, in the District of Columbia, have invented certain new and useful Improvements in Bill-Files, of which the following is a specification.

10 My invention relates to that class of bill files which comprise a file-board and arches secured theron, or other suitable paper-holding devices, adapted to retain letters, bills and other papers.

15 One feature of my invention relates to a bill-file the paper-holding devices of which are composed of stationary arch-members and movable arch-members, the separation of these parts being adapted to permit the impaling or placing of papers on the arches.

20 It is the object of this invention to provide for a bill file comprising a file-board and suitable paper-holding devices, a cover of convenient and improved construction adapted to inclose and protect the papers which the file contains and to be readily opened to permit the free inspection of the contents of the file.

25 A further object of my invention is to provide for a bill file, with or without a cover, a paper-holding device of very simple and cheap construction which may if desired be permanently filed away with its attached papers.

With such objects in view my invention 30 consists in the parts and combinations thereof hereinafter more particularly set forth and claimed.

In order to make my invention more clearly understood, I have shown in the accompanying drawings means for carrying it into practical effect, without limiting my improvements in their useful applications to the particular construction which, for the sake of illustration, I have delineated.

45 In said drawings—Figure 1 is a perspective view of a bill-file embodying my improvements, the cover being shown in its closed position. Fig. 2 is a similar view with the file opened to permit the inspection of its contents. Fig. 3 is a perspective view on a larger scale of a paper-holding device embodying certain features of my invention, which may

be employed with the herein described file-board and cover. Fig. 4 is a similar view, the movable arch-members of the device being thrown open to permit papers to be applied to or removed from the file. Fig. 5 is a perspective view of a securing plate for attaching the paper holder to the file-board.

55 Referring to the drawings, 1 indicates the file-board provided with a suitable paper-holding device, and having hinged thereto at the upper end a cover 2. Such hinging may be effected along the line 3 by a strip of leather or muslin or in any other preferred manner. The main portion of the cover is indicated at 4 and is provided with side pieces 5 and an end piece 6, these latter parts being properly secured to the portion 4 and to each other.

70 7 is an end piece forming a portion of the cover and by means of which the latter is hinged to the file-board as above mentioned. The end piece 7 is also flexibly connected with the portion 4 along the line 8, so that 75 the file may be fully opened as seen in Fig. 2.

75 9, 9 indicate side flaps hinged to the file-board at the sides thereof along the lines 10, and adapted to lie flat in the same plane with the file-board as seen in Fig. 2, or to be folded 80 up against the sides of the pieces 5 and clasped thereto by suitable fastening devices 11, when the cover is closed, as best seen in Fig. 1. When the parts are in this latter position, it will be observed that the contents of the file 85 are entirely inclosed and preserved from inspection and protected from dust or injury.

90 The paper-holding device which embodies certain features of my improvement comprises a base plate 12, which may be of comparatively thin sheet metal, and is formed at 13 with perforations through which pass the stationary members of the arches. Said members are indicated at 14 and are formed at their lower ends with flat heads 15, which are 95 adapted to lie against the surface of the plate 12 in contact with which they are held by solder or by a confining plate or flange 16. By this means the stationary arch-members may be very cheaply assembled with the plate and 100 in such a manner as to have a rigid and durable attachment thereto. The upper ends of the arch-members 14 are adapted to be overlapped by the ends of the movable arch-mem-

bers hereinafter described, and in order to provide for a secure engagement of the arch-members with each other when thus overlapped, I form the ends of either the movable or the stationary arch-members with grooves or sockets in which the ends of the other arch-members may rest. In the construction illustrated, said recesses are shown as formed in the stationary arch-members 14 and are indicated at 17.

The movable arch-members are shown at 18 and are formed preferably of a single piece of wire, the ends of which are curved into the usual arches and the middle of which connects the members 18 and forms a transverse journal 19, adapted to be held in bearings upon the base plate and upon which the movable arch members may oscillate toward and from the members 14.

20 indicates a bearing or bearings formed upon the plate 12, and preferably by bending up a portion or portions thereof, as illustrated in the drawings. 21 indicates notches or apertures in said bearings through which the arch-members 18 pass while their journal 19 is held within the bearings. The manner in which said arch-members are inserted in the apertures 21 in assembling the parts of the device is shown in dotted lines in Fig. 4. After the journal 19 is in place within the bearing the front edge of the latter may be bent down slightly so as to securely confine it. The apertures 21 are so situated that in turning the members 18 toward the stationary arch-members 14, the edges of the apertures will be encountered by the vertical portions of the arch-members 18 before the points of the latter have come into engagement with the recesses 17. Thereafter the continuation of said movement or turning will be accompanied by a slight bending of the arch members 18 or of the bearings 20, or of the plate 12, and the resilience of one or the other of said parts will, after the points of the arch-members 18 have been caused to pass by the arch-members 14 and to the front side of the latter, cause said points to be drawn back into the recesses 17 and securely hold together the stationary and movable arch-members until such time as their disengagement is desired. To effect the latter it is only necessary to draw the arch-members 18 slightly forward, spring them slightly out of line with the arch-members 14 and permit the elasticity of the parts to draw the movable arch-members back into the position shown in full lines in Fig. 4.

While the paper holder may be attached to the file board in various ways, I prefer that illustrated in Fig. 5, in which 22 is a plate of sheet metal, such as tin, which is adapted to be securely clamped to the file-board 12, as by tangs 23 which may pass through the board and be clinched upon its back.

24 is a tongue bent upward and forward from the top edge of the plate 22, and adapted to pass between the plate 12 and the journal 19, as seen in Fig. 2. The bearings

20 abutting the tongue 24 on each end serve to keep the paper-holding device from lateral displacement.

25 is a projection or flap formed on the lower or front edge of the plate 22 and adapted when the plate 12 is in place to be bent over its front edge and down upon its top surface as seen in Fig. 2.

70

75

I claim—

1. In a bill-file, the combination, with a file board provided with the paper-holding device, of a cover hinged to the upper end of said board, and side flaps hinged to the sides 80 of the boards and adapted to clasp upon the cover when the latter is in place over said paper-holding device, substantially as set forth.

2. In a bill file, the combination, of a file 85 board provided with a paper-holding device, a cover hinged to the upper end of said board and having end and side pieces, and side flaps hinged to the sides of the file board and adapted to be clasped over the side pieces of 90 the cover when the latter is in place, substantially as set forth.

3. In a bill file, the combination, of a file 95 board provided with paper-holding arches, of a cover hinged to the upper end of said board and having side and end pieces, and having next to the file board an end piece hinged to said board and hinged to the main portion of the cover, and side flaps hinged to the file 100 board and adapted to be secured to the cover when the latter is in place.

4. In a bill file, a base plate provided with a malleable bearing or bearings 20 having apertures and separated at one side from said plate, arch-members rigidly affixed to said 105 plate, and movable curved arch-members formed with a bottom transverse bar, having their vertical portions passed through said apertures, and the said transverse bar situated within said bearing or bearings, the ends 110 of said arch-members being adapted to overlap and engage each other as described.

5. In a bill file, the combination, of a base 115 plate provided with fixed arch-members and having a portion bent up to form a malleable bearing or bearings separated from the plate at one side and provided with apertures, and movable curved arch-members having transverse connecting bar at their lower ends situated within said bearing or bearings and having their vertical portions passed through said apertures, the ends of one set of said 120 arch-members being provided on their sides opposite to the other arch-members with grooves or sockets in which the ends of said 125 other arch-members are adapted to rest, substantially as set forth.

6. In a bill file, a base plate having fixed 130 arch-members and movable curved arch-members, the latter being provided with a transverse bar, and elastic bearings on said plate separated from the plate at one side adapted to receive said transverse bar, and having apertures for the vertical portions of said

movable arch-members, substantially as set forth.

7. In a bill file the combination with a paper holding device comprising a base-plate, a bearing or bearings thereon, stationary arch-members, and movable arch-members having a journal held in said bearing or bearings, of a securing plate adapted to be attached to the file-board and having a tongue passing

between said journal and base-plate, substantially as set forth.

In witness whereof I have hereunto signed my name in the presence of two witnesses.

WILLIAM O. GOTTWALS.
